ANTIKNOCK FITTING

Anthony J. Luzynski, Philadelphia, Pa.

Application June 13, 1956, Serial No. 591,157

1 Claim. (CL 137—533.21)

The present invention relates to antiknock fittings, and is concerned primarily with an improvement over the fitting disclosed in Patent No. 2,742,928, dated March 13, 1955.

The patent is directed to an invention which is aimed primarily at the proposition of eliminating knocking when a faucet is closed. As explained in this patent, it was the common practice to provide hot water by utilizing coils which are heated, with the cold-water supply communicating with the intake end of the coil and hot water being drawn off the outlet of the coil. Ordinarily, a faucet was connected to this outlet end; and it has been found that a knocking or hammering is created particularly immediately after the faucet is closed. Attempt has been made to eliminate this hammering, and the fitting of the said patent is believed to be generally satisfactory. However, it has been found that when the faucet is shut off in a rapid or abrupt manner, a slight objectionable noise is present in the piping of a home.

With the foregoing conditions in mind, the present invention has in view as its foremost objective the provision of an improved type of pressure expansion chamber which is designed to completely eliminate this undesirable knocking or noise regardless of how rapidly the faucet is shut off. The improved pressure chamber is designed to accommodate a very high peak back pressure.

A fitting of the type with which this invention is concerned ordinarily comprises a main chamber that includes a valve seat and a baffle, the upper edge of the baffle being spaced from the valve seat. Directly below the valve seat there is an intake connection that is connected to the hot water coil. The casing extends outwardly from one side of the baffle and is provided with a connection to which a faucet is adapted to be connected. The casing is continued up above the valve seat and at one side is formed with a by-pass connection. Above this by-pass connection there is another connection to which the pressure chamber is connected. The by-pass is connected to the cold-water supply, and a valve that cooperates with the valve seat is mounted in a guide that is carried by the baffle.

An important object of the present invention is to provide, in a fitting of the character noted, a pressure chamber which consists essentially of a casing in which is mounted a Sylphon-type bellows. This bellows communicates with the casing above the valve seat, and is normally maintained in a collapsed condition by an expansion coil spring. This spring is disposed about a piston, which is in turn carried by the bellows; and the piston is received in a cylinder which constitutes a reduced extension of the casing. The piston is formed with a bleeder groove to prevent the entrapment of air in this casing.

When the faucet is shut off, the high back pressure first unseats the valve and is then effective in the bellows to expand the latter against the influence of the spring. After the back pressure has been fully dissipated, the bellows under the influence of the spring tends to return to its normal original condition, which closes the valve

seat and causes some water to be returned to the by-pass and recirculated through the heating coil.

Various other more detailed objects and advantages of the invention, such as arise in connecting with carrying out the above-noted ideas in a practical embodiment, will in part become apparent and in part be hereinafter stated as the description of the invention proceeds.

The invention therefore comprises an antiknock fitting of the general type disclosed in the patent above identified but which includes a novel and improved pressure chamber. This pressure chamber consists of a casing that is mounted on the connection used for the pressure chamber in the patent, and which casing includes a Sylphon-type bellows that is spring-biased, together with appropriate means for guiding the spring action.

For a full and more complete understanding of the invention, reference may be had to the following description and accompanying drawings, wherein:

Figure 1 is a vertical section through an antiknock fitting designed in accordance with the precepts of this invention; and

Figure 2 is a view in side elevation, somewhat diagrammatic, showing the manner in which this antiknock fitting is included in a hot-water circulatory system.

Referring now to the drawing, wherein like reference characters denote corresponding parts, and first more particularly to Figure 2, a heating coil is therein illustrated and referred to in its entirety by the reference character C. The coil C includes an intake end at 10 and an outlet 25 at 11. A cold-water supply is represented at 12 and is connected to the intake 10, with a by-pass connection being indicated at 13. The fitting of this invention is referred to in its entirety by the reference character F and is connected to the upper end of the outlet 11.

Referring now more particularly to Figure 1, the fitting F comprises a casing including a main body portion 14 that is generally cylindrical and with which communicates an outwardly extending conduit 15 which terminates at a connection 16 to which a faucet or other suitable comparable device may be connected. Such a faucet is represented at 17 in Figure 2.

The upwardly extending main body portion 14 of the fitting F is formed with a valve seat 18 immediately above the joinder of the conduit 15 thereon. A baffle 19 is shown as having its lower edge connected to the casing at the bottom of the conduit 15; and this baffle 19 is inclined over into the upwardly extending casing part 14, with its upper edge being spaced from the valve seat 18. A valve member 20 takes the form of a disc valve having a stem 21 that is received in a guide 22 that is carried by the baffle 19 at its upper edge. This valve member 20 is adapted to assume either the upraised position relative to the valve 18 which is illustrated in Figure 1 or be seated thereon as will be later described. The valve disc 20 is formed with an aperture 23 through which cold water is adapted to pass when the valve is in closed position.

The fitting F is formed with a connection at 24 to which the upper end of the outlet 11 of the coil C is adapted to be connected, such as by being threaded therein in the manner illustrated in Figure 1.

Above the valve seat 18, the upwardly extending portion of the casing 14 is formed with a by-pass connection 25. A by-pass conduit 26 has one end secured to this connection 25 and its other end to the by-pass connection 13.

Carried by the main body portion 14 of the fitting F is an upwardly extending cylindrical part 28 that is internally threaded. A casing 29 carries a nipple 30 that is exteriorly threaded and screwed into the extension 28. This casing 29 is of generally cylindrical formation having a bottom end wall 30 and an upper end wall 31 that

is formed with a cylindrical extension 32 that is coaxial with the casing 29.

Positioned within the lower portion of the casing 29 is a Sylphon-type bellows diaphragm 34 having an intake end at 35 that communicates with the nipple 30. This diaphragm 34 has a closed top wall 36 which carries a piston 37. This piston 37 is formed with a longitudinally-extending groove 38 in a portion of its length and is adapted to be slidably received in the cylindrical extension 32. The purpose of the groove 38 is to prevent air being entrapped in the upper end of the cylindrical extension 32 and thus interfere with operation of the diaphragm.

Surrounding the piston 37 is an expansion coil spring 39 which bears against the end wall 31 at one end and the top wall 36 of the bellows 34 at the other end. The normal tendency of the spring 39 is to urge the bellows into the collapsed position depicted by full lines in Figure 1.

Operation

While the mode of operation of the antiknock fitting of this invention is believed to be obvious from the illustration of the drawing and description of parts given, it may be briefly outlined as follows:

Under normal conditions, that is, with the faucet 17 closed, the valve disc 20 will be seated on its seat 18. When the faucet 17 is opened, the spring 39 will first tend to collapse the bellows 34 to the extent necessary to equal the pressure remaining in the pressure head in the line. Thus some water will be forced out of the bellows 34, which is accompanied by a partial collapse of the bellows.

When the faucet 17 is opened, hot water will be drawn from the conduit 15. In order for this action to take place, the hot water must pass upwardly from the coil outlet 11 and around the upper edge of the baffle 19 beneath the valve seat 18 and disc 20. As the hot water so passes, a small amount of cold water will be drawn through the aperture 23 and mixed with the hot water.

When the faucet 17 is closed, a back pressure on the water in the line is immediately created. This back pressure is effective to at first raise the valve disc 20 from its seat 18. This permits hot water to pass upwardly through the main body part 14 of the casing and into the interior of the bellows 34, thus causing an expansion of the bellows that is accompanied by a compression of the spring 39 and a compression of the air in the casing 29 above the bellows. This action is continued until the back pressure is completely dissipated.

It is evident, of course, that some of the back pressure will be diverted back to the by-pass 26, which will cause a recirculation of the water through the coil C. As the normal pressure in the line is gradually restored at the faucet 17, or more particularly in the conduit 15, the valve disc 20 will again be seated on its seat 18 due to the tendency of the bellows to collapse under the influence of the spring 39. This collapsing of the bellows will force water out of the bellows and, inasmuch as the valve

disc 20 is now seated, this water will be diverted back to the by-pass 26 and around through the heating coil.

What actually takes place is that, in place of the abrupt stop which ordinarily would be caused by a closing of the faucet, the water is recirculated back through the by-pass, with the recirculation being spread over a longer interval by the bellows 34 and spring 39. It is this arrangement of providing for a recirculation over a relatively long period which completely eliminates all hammering or knocking which now actually takes place in installations of this type.

While a preferred specific embodiment of the invention is hereinbefore set forth, it is to be clearly understood that the invention is not to be limited to the exact constructions, mechanisms, and devices illustrated and described, because various modifications of these details may be provided in putting the invention into practice within the purview of the appended claim.

What is claimed is:

20 In an antiknock fitting, a cylindrical casing having an inlet and an outlet, a conduit near the inlet of said casing outstanding laterally therefrom, a valve seat in said casing adjacent to the wall of said conduit nearest the outlet, a baffle having one end joined to the wall of said conduit adjacent to the inlet with the other end thereof being inclined toward the center of said casing in adjacent spaced relation with said valve seat, a valve disc cooperating with said valve seat on the side thereof opposite from said conduit, guide means for said valve disc, a faucet connection at the free end of said conduit, a by-pass connection on said casing adjacent to the valve seat and valve disc on the outlet side thereof, a connection for a pressure chamber in the outlet end of said casing, a casing having upper and lower walls, said lower wall being provided with a nipple attached to said connection for the pressure chamber and being otherwise imperforate, said casing being formed with a cylindrical extension extending upwardly from said upper wall, a Sylphon type bellows in the lower part of said casing having an inlet communicating with said nipple and an end wall, a piston carried by said end wall and extending into said extension, said piston being formed with a longitudinally-extending groove communicating with the upper free end thereof, and an expansion coil spring disposed about said piston and engaging the end wall of said bellows and the upper wall of said casing.
